UNITED STATES PATENT OFFICE.

HERBERT R. KEITHLEY, OF BUFFALO, NEW YORK.

UNDERFRAME FOR RAILWAY-CARS.

SPECIFICATION forming part of Letters Patent No. 659,401, dated October 9, 1900.

Application filed April 24, 1900. Serial No. 14,093. (No model.)

To all whom it may concern:

Be it known that I, HERBERT R. KEITHLEY, a citizen of the United States, and a resident of Buffalo, in the county of Erie and State of 5 New York, have invented a new and useful Improvement in Underframes for Railway-Cars, of which the following is a specification.

The object of my invention is to provide a steel underframe for railway-cars which combines with a minimum weight of metal a maximum degree of strength and rigidity, so as to effectually withstand the severe shocks to which cars are subjected.

In the accompanying drawings, Figure 1 is 15 a fragmentary side elevation of my improved underframe. Fig. 2 is a transverse section in line 2 2, Fig. 1. Fig. 3 is an end view of the underframe.

Like letters of reference refer to like parts 20 in the several figures.

A represents the metallic side sills of the underframe, B the center sill, and C one of the body-bolsters. Each side sill comprises 25 a flat horizontal top plate a , two vertical webs a' , extending downwardly from the edges of said top plate, and horizontal flanges a^2 , projecting outwardly from the lower edges of said webs, as shown in Fig. 2.

The center sill B is composed of a horizontal 30 or bottom plate b , two vertical webs b' , extending upwardly from the edges of said plate, and horizontal flanges b^2 , projecting outwardly from the upper edges of said webs, as shown in Fig. 2. Each of the sills A and B 35 is formed from a single plate of pressed or rolled steel. The bottom plate of the center sill is riveted or bolted to the upper flanges of the bolster C, and the lower flanges of the side sills A are also riveted to said bolster-flanges. If desired, the sills may be reinforced by longitudinal tension-plates D, which 40 are riveted to their bottom flanges a^2 , thus making these sills practically box-girders, as shown.

E represents the steel floor-plates, which extend across the top of the side and center sills and which are riveted to the flanges b^2 of the center sill and the top plates a of the side sills. In the construction shown in the drawings 45 the two floor-plates are lapped together directly over the center sill and riveted to the

flanges of the latter, by which construction the center sill forms practically a box-girder of great transverse and lateral strength and stiffness.

55

A side or center sill constructed as herein shown and described amounts in effect to two Z-bars arranged to face and brace each other and formed of one integral piece of metal. The lateral strength and stiffness of 60 a sill of this cross-section greatly exceeds that of two pressed-steel channels or channel-bars of the same depth and metal section. A center sill of this improved construction will withstand buffing and collision shocks to the greatest advantage, taking the same in direct 65 compression and transmitting and distributing the shocks throughout the underframe by means of the floor-plates and the body-bolsters, which are riveted directly to the center 70 sill. Owing to the strength of such a sill a single center sill may be employed, as shown in the drawings, instead of a plurality of sills, as has hitherto been the common practice.

Each body-bolster is preferably composed 75 of a pair of Z-bars having their upper flanges arranged to face outwardly or in opposite directions and united by top and bottom plates ff' , which are riveted directly to the flanges of said bars, thus forming practically a box- 80 girder, as shown in Fig. 1. The girder so formed is bent upwardly on opposite sides of the center sill and riveted through a third or intermediate tie-plate g to the two side sills, as shown. The intermediate plate g passes 85 over the top of the center sill and forms, with the body-bolster, a diamond-shaped truss of great strength and stiffness.

The ends of the side and center sills are rigidly tied together by two horizontally-arranged Z-bars $h h'$, which extend across the upper and lower sides of said sills, so that their front flanges overlap the ends of the sills, as shown in Figs. 1 and 3. I is a horizontal channel-bar which extends across the ends of the side and center sills and embraces the two Z-bars $h h'$. These Z-bars and the channel-bar I are secured to the end and center sills by rivets, which pass through the flanges of said channel-bar, the Z-bar, and the adjacent portions of the sills.

side and center sills and the bolsters, is applicable to any type of railway-cars in general use.

If desired, the position of the center sill 5 may be inverted, the horizontal plate b being located at the top of the sill and the flanges b^2 at the bottom thereof. The side sills may also be inverted, if desired.

I claim as my invention—

10 1. An underframe for a railway-car having a side sill constructed of a single piece of metal and composed of a longitudinal plate and vertical webs arranged at the edges of said plate and each provided at its free edge 15 with an outwardly-extending flange, substantially as set forth.

2. An underframe for a railway-car having a center sill constructed of a single piece of metal and composed of a longitudinal plate 20 and vertical webs arranged at the edges of said plate and each provided at its free edge with an outwardly-extending flange, said sill being formed from a single piece of metal, substantially as set forth.

25 3. An underframe for a railway-car having side sills, a single center sill constructed of an integral piece of metal and composed of a longitudinal plate and vertical webs arranged at the edges of said plate and each provided 30 at its free edge with an outwardly-extending flange, and a bolster connecting said side and center sills, substantially as set forth.

4. An underframe for a railway-car having side sills each constructed of a single piece of metal and composed of a longitudinal plate 35 and vertical webs arranged at the edges thereof and each provided at its free edge with an outwardly-extending flange, a center sill constructed of a single piece of metal and composed of a longitudinal plate and vertical 40

webs arranged at the edges thereof and each provided at its free edge with an outwardly-extending flange, and a bolster connecting said side and center sills, substantially as set forth.

45

5. An underframe for a railway-car having a side sill composed of a horizontal top plate and vertical webs extending downwardly from the edges of said plate and each provided at its lower edge with an outwardly-extending flange, and a longitudinal bottom plate riveted to said flanges, substantially as set forth.

50

6. The combination with the side and center sills, of a body-bolster composed of a pair of **Z**-bars and top and bottom plates riveted to the flanges of said bars, and a tie-plate passing over the top of the center sill and having its end portions riveted between the body-bolster and the side sills, substantially as set forth.

55

7. The combination with the side and center sills, of a pair of horizontally-arranged **Z**-bars extending across the end portions of said sills on their upper and lower sides, substantially as set forth.

60

8. The combination with the side and center sills, of a pair of horizontally-arranged **Z**-bars extending across the end portions of said sills on their upper and lower sides, and a channel-bar embracing the ends of said sills and said upper and lower **Z**-bars and riveted to the same, substantially as set forth.

70

Witness my hand this 13th day of April, 1900.

HERBERT R. KEITHLEY.

Witnesses:

CYESTA HORNBECK,
JNO. J. BONNER.
